SPEED GOVERNING PUMP

Herbert C. Edwards, Massillon, Ohio, assignor to
The Timken Roller Bearing Company, Canton,
Ohio, a corporation of Ohio

Application June 9, 1938, Serial No. 212,652

11 Claims. (Cl. 123—140)

This invention relates to speed regulating devices for internal combustion engines, particularly engines of the type having fuel injection systems including a main fuel injection pump and an auxiliary pump for supplying fuel to the main pump. The principal object of the present invention is to utilize the discharge pressure of the supply pumps of such fuel injection systems for automatically controlling the speed of the engine at both idling and high speeds in all throttle positions. Other objects are simplicity and economy of construction and compactness of design. The invention consists in the speed governing fuel supply pump and in the construction, combinations and arrangements of parts hereinafter described and claimed.

In the accompanying drawings, which form part of this specification and wherein like symbols refer to like parts wherever they occur,

Fig. 1 is a vertical transverse section through a speed governing pump embodying my invention, the section being taken on the axis of the rotary pump mechanism on the line 1—1 in Fig. 2;

Fig. 2 is a vertical longitudinal section on the line 2—2 in Fig. 1;

Fig. 3 is a vertical transverse section along the axis of the governor mechanism on the line 3—3 in Fig. 4;

Fig. 4 is a transverse section on the line 4—4 in Fig. 3; and

Figs. 5 and 6 are horizontal sections on the lines 5—5 and 6—6, respectively, in Fig. 1.

The device illustrated in the accompanying drawings is adapted to be embodied in the fuel supply system of a compression ignition engine and constitutes a pump for supplying fuel to the injection pump of said system and a hydraulic governor for automatically regulating the speed of the engine by controlling the volume of fuel delivered thereto by said injection pump, of which only the reciprocating fuel control rod A and the rotary cam shaft B are shown. Said device comprises a housing 1 containing a suitable pump mechanism and a chamber 2 adapted to receive an extension of the cam shaft B. Said pump mechanism preferably comprises two uprights shafts 3 and 4 having intermeshing right and left-hand worms 5 and 6 in bearing contact with a bore 7 provided therefor in the housing 1. The lower portion of the upright shaft 3 is disposed alongside of the shaft extension B and has a helical gear 8 rigid therewith that intermeshes with and is driven by a similar gear 9 on said extension. The upper and lower ends of the

worm shaft 3 are supported in roller bearings 10 provided therefor in the upper and lower ends of the housing 1; and the lower end of the other or shorter worm shaft 4 turns on a removable seat 11 provided therefor in said housing. 5

The lower ends of the intermeshing worms 5 and 6 work in an inlet chamber 12 which is formed in the housing at the lower end of the worm receiving bore 7 and is supplied with fuel through an inlet passageway 13 provided with a suitable ball check valve 14; and the upper end of said bore opens into the bottom of an outlet chamber 15 having an adjustable discharge orifice 16. Located in the outlet chamber 15 is a horizontal sleeve 17, which extends through one end wall of the housing 1 and abuts against the opposite end wall thereof where it is supported by an outlet fitting 18 that is threaded into said sleeve, rests in a bore provided therefor in said last mentioned end wall and is threaded exteriorly thereof to receive a conduit (not shown) for conveying the fuel to the injection pump. The fitting 18 is provided at its inner end with a tapered seat which cooperates with the tapered end of a needle valve 19 to form the adjustable discharge orifice 16. The needle valve 19 is threaded into the sleeve 17 through the exposed end thereof and is provided with a nut 20 for locking it in the desired position of axial adjustment. Communication is established between 30 the outlet chamber 15 and the outlet sleeve 17 by means of a port or opening 21 in the latter.

Reciprocable in a horizontal bore 22 formed in the housing parallel to the axis of the sleeve 17 is a pressure responsive member or piston 23, 35 which cooperates with the inner end portion of said bore to form a chamber or cylinder 24 that communicates through an inclined passageway 25 with a vertical bore 26 formed in the pump housing between and in communication with the outlet chamber 15 and an overflow chamber 27 that communicates through a passageway 28 with the inlet chamber. The control rod A of the main or injection pump extends into the horizontal bore 22 of the housing 1 and is yieldably held in abutting relation to the piston 23 therein by means of a coil spring 29, one end of which bears against a seat A' provided therefor on the control rod and the other end of which is adapted to bear against a seat (not shown) provided therefor on the adjacent end of the injection pump. 40

Mounted in the vertical bore 26 that opens at its upper end into the outlet chamber 15 and at its lower end into the overflow chamber 27 is a sleeve 30 having a radial port 31 therein that 55

is in continuous communication with the inclined passageway 25 leading from the cylinder 24 to said bore. This sleeve is adapted to be adjusted axially in the bore 26 by means of a 5 manually operable throttle shaft 32 that is journaled in the housing 1 and is provided with an eccentric pin 33 which works in the slot 34 provided therefor in a depending skirt portion 35 at the lower end of said sleeve. The sleeve 30 10 constitutes a cylinder for a piston 36 that is responsive to the pressure of the fuel in the outlet chamber 15. This piston has one or more radial ports 37 therein adapted to be brought into register with the port 31 in the sleeve 30. The piston 36 is suspended from the lower end of a coil tension spring 38 whose upper end is fixed to the lower end of a screw 39, which is threaded through the upper portion of the housing 1 so as to regulate the tension of said spring and is 15 locked in the desired position of adjustment by means of a packing nut 39a.

By the arrangement described, the pumping effect produced by the rotating worms 5 and 6 unseats the inlet valve 14 and draws fuel through 25 the intake passageway 13 into the inlet chamber 12. The fuel is then transferred by the upwardly advancing intermeshing threads of the two worms from the inlet chamber 12 into the outlet chamber 15 where it is forced into the needle valve 30 supporting sleeve 17 through the port 21 therein and is thence discharged through the adjustable discharge orifice 16 into the outlet fitting 18 which forms part of the conduit leading to the fuel injection pump.

The piston 36 in the cylinder 30 is also subjected to the pressure of the fuel in the outlet chamber 15 so that, when the speed of the supply pump increases due to an increase in engine speed, the pressure in said outlet chamber also increases, thereby forcing said piston downwardly in said cylinder against the tension of its supporting spring 38. When such pressure is sufficient to move the piston 36 downwardly far enough to bring the upper end thereof below the upper edge of the port 31 of the cylinder 30, communication is established between the outlet chamber 15 and the control rod operating cylinder 24 through the passageway 25, thereby causing the pressure to act on the piston 23 and force the control rod A axially in the direction of reduced fuel feed against the pressure of the spring 29 and cut down the volume of fuel delivered to the engine by the injection pump.

When the speed of the engine decreases, the 55 speed of the rotary pump is also decreased, thereby reducing the pressure in the outlet chamber and permitting the spring 38 to raise the piston 36 and cut off communication between the outlet chamber 15 and the control rod operating 60 cylinder 24 and establish communication between said cylinder and the overflow chamber 27 through the passageway 25 and ports 31 and 37 and thus permit the spring 29 to move the control rod A in the direction of maximum fuel 65 feed. Thus, as the load on the engine varies, there is a corresponding variation in the pressure of the fuel in the outlet chamber of the fuel supply pump and in the volume of fuel fed to the engine by the injection pump, thereby maintaining a predetermined constant engine speed.

The governor may be set for the desired engine speed or the engine manually controlled by operating the control shaft 32 to shift the sleeve 30 axially of the piston therein and thus vary the relative positions of the ports 31 and 37. The

size of the discharge orifice 16 may be adjusted to suit the tested characteristics of the engine by means of the needle valve 19 which is then locked in the desired position of adjustment; and the piston supporting spring 38 may be initially set at the desired tension by means of the adjusting screw 39.

What I claim is:

1. In a fuel supply system for an internal combustion engine, a fuel pump operable by the engine and having outlet and overflow chambers and a cylinder, a member for controlling the feed of fuel to the engine, spring means for urging said control member in the direction of maximum fuel feed, a pressure responsive member in said cylinder for moving said control member in the direction of minimum fuel feed, and means operable by a predetermined pressure of fuel in said outlet chamber to establish communication between the latter and said cylinder and thus actuate said pressure responsive member and move said control member in the direction of minimum fuel feed and operable when the pressure of the fuel in said outlet chamber falls below said predetermined pressure to establish communication between said cylinder and said overflow chamber to thereby relieve the pressure in said cylinder and thus cause said spring means to move said control member in the direction of maximum fuel feed.

2. In a fuel supply system for an internal combustion engine, a fuel pump operable by the engine and having inlet and outlet chambers and a cylinder, a member for controlling the feed of fuel to the engine, spring means for urging said control member in the direction of maximum fuel feed, a pressure responsive member in said cylinder for moving said control member in the direction of minimum fuel feed, and a second pressure responsive member for establishing communication between said outlet chamber and said cylinder or between the latter and said inlet chamber, said second mentioned pressure responsive member being operable by a predetermined pressure of fuel in said outlet chamber to establish communication between the latter and said cylinder to thereby actuate the pressure responsive member therein to move said control member in a direction which will reduce the supply of fuel fed to the engine, said second pressure responsive member being adapted when the pressure of the fuel in the discharge chamber falls below said predetermined pressure to establish communication between said cylinder and said inlet chamber, thereby relieving the pressure on the pressure responsive member in said cylinder and thus cause said spring means to move said control member in a direction that will increase the amount of fuel supplied to the engine.

3. In a fuel supply system for an internal combustion engine, a speed controlling fuel pump operable by the engine and having inlet, outlet and overflow chambers and a cylinder, a member for controlling the feed of fuel to the engine, yieldable means for moving said control member in the direction of maximum fuel feed, a piston in said cylinder for moving said control member in the direction of minimum fuel feed, a second cylinder communicating at one end with said outlet chamber and at the other end with said overflow chamber and intermediate said ends with said first mentioned cylinder, a piston in said second cylinder operable by a predetermined maximum pressure of the fuel in said outlet chamber to establish communication between

the latter and said first mentioned cylinder to thereby actuate the piston therein and move said control member in the direction of minimum fuel feed, and means operable at a predetermined minimum pressure of the fuel in said outlet chamber to actuate the piston in said second cylinder and cut off communication between said cylinders and establish communication between said first mentioned cylinder and said overflow chamber to thereby relieve the pressure on the piston in said first mentioned cylinder and thus permit said yieldable means to move said control member in the direction of maximum fuel feed.

4. In a fuel supply system for an internal combustion engine, a speed controlling fuel pump operable by the engine and having inlet, outlet and overflow chambers and a cylinder, said outlet chamber having an adjustable discharge orifice, a member for controlling the feed of fuel to the engine, yieldable means for moving said control member in the direction of maximum fuel feed, a piston in said cylinder for moving said control member in the direction of minimum fuel feed, a second cylinder communicating at one end with said outlet chamber and at the other end with said overflow chamber and intermediate said ends with said first mentioned cylinder, a piston in said second cylinder operable by a predetermined maximum pressure of the fuel in said outlet chamber to establish communication between the latter and said first mentioned cylinder to thereby actuate the piston therein and move said control member in the direction of minimum fuel feed, means operable at a predetermined minimum pressure of the fuel in said outlet chamber to actuate the piston in said second cylinder and cut off communication between said cylinders and establish communication between said first mentioned cylinder and said overflow chamber to thereby relieve the pressure on the piston in said first mentioned cylinder and thus permit said yieldable means to move said control member in the direction of maximum fuel feed, and manually operable means for adjusting said second cylinder axially of the piston therein.

5. In a fuel supply system for an internal combustion engine, a fuel injection pump including a shaft driven by the engine, a member for controlling the feed of fuel to the engine and yieldable means for moving said control member in the direction of maximum fuel feed, a pump driven by said shaft for supplying fuel to said injection pump, said supply pump having inlet, outlet and overflow chambers and a cylinder, a piston in said cylinder for moving said control member in the direction of minimum fuel feed, a second cylinder communicating at one end with said outlet chamber and at the other end with said overflow chamber and intermediate said ends with said first mentioned cylinder, a piston in said second cylinder operable by a predetermined pressure of the fuel in said outlet chamber to establish communication between the latter and said first mentioned cylinder to thereby actuate the piston therein and move said control member in the direction of minimum fuel feed, and means operable at a predetermined pressure of the fuel in said outlet chamber to actuate the piston in said second cylinder and cut off communication between said cylinders and establish communication between said first mentioned cylinder and said overflow chamber to thereby relieve the pressure on the piston in said first mentioned cylinder and thus permit said yieldable

means to move said control member in the direction of maximum fuel feed.

6. In a fuel supply system for an internal combustion engine, a speed controlling fuel pump operable by the engine and having inlet, outlet and overflow chambers and a cylinder, a member for controlling the feed of fuel to the engine, a spring for moving said control member in the direction of maximum fuel feed, a piston in said cylinder for moving said control member against the pressure of said spring in the direction of minimum fuel feed, a second cylinder communicating at one end with said overflow chamber and at its other end with said outlet chamber and intermediate said ends with said first mentioned cylinder, a piston in said second cylinder operable by relatively high pressure of the fuel in said outlet chamber to establish communication between said cylinders and to cut off communication between said first mentioned cylinder and said overflow chamber, and a spring operable during a relatively low pressure of the fuel in said outlet chamber to move the piston in said second cylinder to cut off communication between said cylinders and to establish communication between said first mentioned cylinder and said overflow chamber.

7. In a fuel supply system for an internal combustion engine, a speed controlling fuel pump operable by the engine and having inlet, outlet and overflow chambers and a cylinder, said outlet chamber having an adjustable discharge orifice, a member for controlling the feed of fuel to the engine, a spring for moving said control member in the direction of maximum fuel feed, a piston in said cylinder for moving said control member against the pressure of said spring in the direction of minimum fuel feed, a second cylinder communicating at one end with said overflow chamber and at its other end with said outlet chamber and intermediate said ends with said first mentioned cylinder, a piston in said second cylinder operable by relatively high pressure of the fuel in said outlet chamber to establish communication between said cylinders and to cut off communication between said first mentioned cylinder and said overflow chamber, and a spring operable during a relatively low pressure of the fuel in said outlet chamber to move the piston in said second cylinder to cut off communication between said cylinders and to establish communication between said first mentioned cylinder and said overflow chamber.

8. In a fuel supply system for an internal combustion engine, a speed controlling fuel pump comprising a housing having inlet, outlet and overflow chambers, a bore communicating at one end with said overflow chamber and at the other end with said outlet chamber, a cylinder and a passageway communicating with said bore and cylinder, a rotary pump mechanism operable by the engine and communicating at its inlet end with said inlet chamber and at its outlet end with said outlet chamber, a member for controlling the feed of fuel to the engine, a spring for moving said control member in the direction of maximum fuel feed, a piston in said cylinder for moving said control member in the direction of minimum fuel feed, a sleeve in said bore and having a port in communication with said passageway, a piston reciprocable in said sleeve and having a port communicating with said overflow

chamber and adapted to register with the port in said sleeve, and a spring operable during a relatively low pressure of the fuel in said outlet chamber to hold said piston in a position wherein communication is cut off between said outlet chamber and the port in said sleeve and the port in said piston communicates with the port in said sleeve to thereby establish communication between said cylinder and said overflow chamber through said ports and said passageway, said piston being operable by a relatively high pressure of the fuel in said outlet chamber to move against the tension of said spring to thereby uncover the port in said sleeve and thus establish communication between said outlet chamber and said cylinder through said passageway.

9. In a fuel supply system for an internal combustion engine, a speed controlling fuel pump comprising a housing having inlet, outlet and overflow chambers, a bore communicating at one end with said overflow chamber and at the other end with said outlet chamber, a cylinder and a passageway communicating with said bore and cylinder, a rotary pump mechanism operable by the engine and communicating at its inlet end with said inlet chamber and at its outlet end with said outlet chamber, a member for controlling the feed of fuel to the engine, a spring for moving said control member in the direction of maximum fuel feed, a piston in said cylinder for moving said control member in the direction of minimum fuel feed, a sleeve in said bore and having a port in continuous communication with said passageway, a piston reciprocable in said sleeve and having a port communicating with said overflow chamber and adapted to register with the port in said sleeve, a spring operable during a relatively low pressure of the fuel in said outlet chamber to hold said piston in a position wherein communication is cut off between said outlet chamber and the port in said sleeve and the port in said piston communicates with the port in said sleeve to thereby establish communication between said cylinder and said overflow chamber through said ports and said passageway, said piston being operable by a relatively high pressure of the fuel in said outlet chamber to move against the tension of said spring to thereby uncover the port in said sleeve and thus establish communication between said outlet chamber and said cylinder through said passageway, means for adjusting the tension of said spring, and means for adjusting said sleeve axially to vary the relative positions of the ports in said sleeve and the piston therein.

10. In a fuel supply system for an internal combustion engine, a speed controlling fuel pump

comprising a housing having inlet and overflow chambers, an outlet chamber having an adjustable discharge orifice, a bore communicating at one end with said overflow chamber and at the other end with said outlet chamber, a cylinder and a passageway communicating with said bore and cylinder, a rotary pump mechanism operable by said engine and communicating at its inlet end with said inlet chamber and at its outlet end with said outlet chamber, a member 10 for controlling the feed of fuel to the engine, a spring for moving said control member in the direction of maximum fuel feed, a piston in said cylinder for moving said control member in the direction of minimum fuel feed, a sleeve in said bore and having a port in continuous communication with said passageway, a piston reciprocable in said sleeve and having a port adapted to register with the port in said sleeve, a spring adapted to yieldably hold said piston in a position wherein communication is cut off between said outlet chamber and the port in the piston communicates with the port in said sleeve, said piston being operable by a predetermined pressure of the fuel in said outlet chamber to move against the tension of said spring and place the port in said sleeve in communication with said outlet chamber, a sleeve located in said outlet chamber and in communication therewith, an outlet fitting threaded 20 into said sleeve, and a needle valve mounted in said sleeve and cooperating with said fitting to form said adjustable discharge orifice.

11. In a fuel supply system for an internal combustion engine, a fuel injection pump operable by said engine and including a member for controlling the feed of fuel thereto, a pump operable by said injection pump for supplying fuel thereto, said supply pump having an inlet chamber, an outlet chamber leading to said injection pump, and an overflow chamber and a cylinder, means for moving said control member in the direction of maximum fuel feed, a piston in said cylinder for moving said control member in the direction of minimum fuel feed, and means operable by a predetermined pressure of the fuel in said outlet chamber to establish communication between the latter and said cylinder and thus actuate said piston and move said control member in the direction of reduced fuel feed and operable at a pressure below said predetermined pressure to establish communication between said cylinder and said overflow chamber to thereby relieve the pressure in said cylinder and thus permit said control member to move in the direction of increased fuel feed.

HERBERT C. EDWARDS.
